UNITED STATES PATENT OFFICE.

DANIEL A. SHIRLEY AND CHESTER A. BRAIDWOOD, OF PERTH AMBOY, NEW JERSEY.

DESIGN FOR A FISHING LURE.

Application filed May 15, 1926. Serial No. 17,739. Term of patent 7 years.

To all whom it may concern:

Be it known that we, DANIEL A. SHIRLEY and CHESTER A. BRAIDWOOD, both citizens of the United States, and residents of Perth Amboy, in the county of Middlesex and State of New Jersey, have invented a new, original, and ornamental Design for Fishing Lures, of which the following is a specification, reference being had to the accompanying drawings, forming a part thereof, and of which—

Figure 1 is a face view; Fig. 2 is an edge view, and Fig. 3 is a transverse section on the line 3—3 of a fishing lure showing our new design.

We claim:

The ornamental design for a fishing lure as shown.

DANIEL A. SHIRLEY.
CHESTER A. BRAIDWOOD.
